FLANGE FORMING APPARATUS

Karl Herzog, North Tonawanda, N. Y., assignor
to Curtiss-Wright Corporation, a corporation
of Delaware

Application April 12, 1943, Serial No. 482,793

5 Claims. (Cl. 153—12)

This invention relates to flange forming apparatus and particularly to an apparatus which is suitable for the working of tempered or annealed stock material.

With the usual forming punch and die block apparatus, the article is punched from soft material and then annealed to give to the article its final hardness. The effect of the annealing operation is to throw the flange out of its true angle with the web, if in fact it ever was true or completely formed by the punching operation. All of which requires considerable working by hand with a mallet to bring flanges to the proper angle with the web to give the article its final form. In the aircraft industry where this method of forming parts is used extensively, a great number of man hours are lost because of the added working and handling of the parts.

It is, therefore, an object of the present invention to provide a flange forming apparatus whereby the necessary hand operations inherent with the articles made with present day die arrangements, will be eliminated.

It is another object of the invention to provide a flange forming apparatus which will punch the article directly into its final shape from a stock material which has already been annealed.

According to the present invention, there has been provided in the opening of the die block a grooved cylinder adapted to receive a part of the blank as it is forced into the die opening and arranged to rotate due to the engagement of a spring pad therewith in its downward movement, to wrap the flange against the inwardly inclined or receding face of the forming punch. This inwardly inclined face of the forming punch is at an angle of some 12 degrees or so beyond a perpendicular with the web so that when the annealed material is used, the flange will spring back to its desired 90° angle with the web. The rotation is given to the cylinder by the downward movement of the spring pad which has on its bottom an upwardly and outwardly inclined surface adapted to engage one face of the groove in the roller so as to force the roller about its axis with the other face of the groove bearing against the outer face of the flange to press it against the receding face of the forming punch. The amount of this rotation is therefore measured by the amount of angle given to the inclined face portion of the spring pad. The outer edges of the spring pad are relieved inwardly to permit the rotation of the grooved roller. When the finished article is released from the die block, the flanges will spring outwardly to assume the de-

sired angle. The over-bending of 12° has been found to be sufficient for the usual annealed sheet metal such as is used in the aircraft industry. The apparatus, however, can be adjusted and made for use with any type of material, by altering the amount of inclination of the inclined surfaces on the spring pad and forming punch.

For other objects and for a better understanding of the invention, reference may be had to the following detailed description taken in connection with the accompanying drawings, in which

Fig. 1 is a perspective view of the flange-forming apparatus for one form of an article broken away to show in cross-section some of the parts thereof.

Fig. 2 is a perspective view of the blank used in the arrangement shown in Fig. 1.

Fig. 3 is a perspective view of the final article pressed from the apparatus shown in Fig. 1.

Fig. 4 is a cross-sectional view, in elevation, of the flange-forming apparatus shown in Fig. 1 as taken along the line 4—4 of Fig. 5.

Fig. 5 is also a cross-sectional view, in elevation, taken laterally through the apparatus, both of these views being shown with the forming punch out of engagement and with the blank resting on the die block.

Fig. 6 is a cross-sectional view similar to Fig. 4 showing the die blank partially pressed into the die block and just prior to the flanges thereof being worked by the grooved rollers, the section being taken along line 6—6 of Fig. 7 and looking in the direction of the arrows thereof.

Fig. 7 is a full end view, in elevation, of the apparatus at the same stage of the pressing operation as Fig. 6.

Fig. 8 is a cross-sectional view, in elevation, similar to Figs. 4 and 6 but at the final stage of the pressing operation and after the roller elements have operated to force the flanges against the inwardly inclined faces of the forming punch.

Fig. 9 is an exploded and perspective view of a flange-forming apparatus which is adapted for the fabrication of aircraft ribs with flanges at three sides thereof.

Figs. 10 and 11 are respectively perspective and sectional views of an aircraft rib which is formed from the apparatus shown in Fig. 9, the section of Fig. 11 being taken along the lines 11—11 of Fig. 10.

Referring now particularly to Figs. 1 to 8, there is shown a die block 15 having a forming opening 16 therein and in which there is disposed a spring or biasing pad 17 adapted for movement inwardly and against the action of a spring 18 located

in the die shoe 19. When the pad 17 is at its full height, it is flush with the top face of the die block 15. A blank 20, Fig. 2, previously cut to the proper design is placed on the top of the die with one edge against a stop plate or guide 21 on the top of the die block and another edge against a stop plate 22 on the top of the spring pad. These stop plates serve to properly center and locate the blank over the opening 16 in the die block.

The blank 20 has two side portions 23 and 24 from which full 90° flanges are to be formed. It also has an extension 25 which is to be bent by an inclined block 26 at one end of the opening 16 in the die block 15, which is given only a slight angle with respect to a web 27 of the finished article as shown in Fig. 3. Instead of the blank being of soft material, as is usually the case with the present day methods, the blank is of annealed or hardened material and because of its being so, the portions of it will have a certain defined springiness which must be taken into consideration upon folding of the portions 23 and 24 in the die block so that the article will have these portions angled at 90° as the article is removed from the die block.

In the sides of the opening 16 directly beneath the portions 23 and 24 respectively of the blank 20, there are disposed rollers or cylindrically shaped elements 28 having a 90° angled groove 29 running coextensively along the length of the same. The apex of this groove is at the axial center of the roller and there is provided two faces 30 and 31 which serve in a manner to be described.

On the bottom of the spring pad 17, there are provided downwardly inclined working faces 32 adapted to engage respectively faces 31 of the groove 29 in the roller as the spring pad is forced downwardly. Inasmuch as the faces 32 are inclined, the same upon sliding over the faces 31, will effect a rotative movement of the roller 28 about its axis. The pad is also provided with an inclined or upwardly receding edge 33 so relieved as to permit this turning movement of the roller in order that the upwardly extended face 30 of the groove 29 can be turned to position beyond the edges 33 of the spring pad 17 in a manner as shown in Fig. 8.

This downward movement of the blank 20 has been effected by means of a forming punch 34 having a bottom face 35 which engages the top or web portion 27 of the blank to effect the bending of the portions 23 and 24 over the edges 36 of the opening 16. This step of the bending is shown in Fig. 6. Further movement of the forming punch to the position shown in Fig. 8, causes the rotation of the rollers 28 so that the upwardly extended face 30 of the groove 29 will be brought against flanges 23 and 24 to effectively force the flange upwardly against receding or inclined side faces 38 of the forming punch 34. The amount of rotation of the roller is determined by the angle of inclination of the bottom face portion 33 of the spring pad 17. With the materials such as ordinarily used in the aircraft industry, it has been found that a rotation of the flanges 12° beyond the vertical is sufficient to give a final article a 90° flange upon the article being removed from the die block.

It should now be apparent that there has been provided a flange forming apparatus particularly adaptable for the working of sheet metal which has been hardened or annealed, whereby considerable manual labor has been eliminated in the

manufacture of pressed metal articles which have to be made of hardened stock. The flange-forming apparatus is so constructed that it is readily assembled or disassembled by turning retaining screws 40 and is connected to a punch press base by means of a clamping bracket 41. The rollers 28 are retained in the opening 16 against lateral movement by side plates 42 screwed into the side of the die block 15 by screws 43.

10 Referring now to Fig. 9, there is shown a flange-forming apparatus particularly constructed for the forming of flanges on a wing rib. This forming apparatus includes three grooved rollers so as to provide three flanges 45, 46, and 47 on a finished rib 48. These ribs 48 also have flanged lightening holes 49 which are formed during the same operation in which the flanges are formed.

This forming apparatus includes a die shoe or base 50 on which are located at spaced intervals, 20 a nest of notched blocks 51 respectively having stop plates 52 thereon. These stop plates 52 at their inner edges are rolled downwardly so as to facilitate the movement of portions of the blank 53 over the same upon the blank being pressed 25 downwardly thereover by a forming punch 54 having a downwardly extending contacting or working plate 55 thereon. This contacting plate 55 has receding or inwardly inclined side faces 56 against which the final flanges are pressed by 30 grooved rollers 57 mounted for rotation in the blocks 51.

There is also provided a spring pad 58 having a bottom contacting face 59 adapted to engage a face 60 of a groove 61 in the roller 57. Also the 35 edges of the spring pad 58 are inwardly receded as indicated at 62 so as to permit the rotary motion of the roller 57 as the blank is forced through the last part of the punching operation. The 40 spring pad 58 is supported on a plurality of hydraulic cushioning arrangements, one of which is shown at 63, and located within the base 50. The spring pad 58 also has upwardly extending projections 64 for forming the lightening holes 49.

While various changes may be made in the 45 detail construction of the present apparatus, it shall be understood that such changes shall be within the spirit and scope of the present invention as defined by the appended claims.

I claim as my invention:

50 1. In a flange forming apparatus, a stationary die block having an opening formed therein, a roller mounted in said block at one side of said opening, said roller being rotatable about a fixed axis and being formed with an axially extending channel having side and bottom walls, a yieldingly-supported pad which is located in said opening and upon which a blank may be arranged, and a forming punch which is movable to engage said blank and to force said pad with said blank 55 into said opening, said pad being engageable with the bottom wall of said channel to rotate said roller and thereby cause the side wall of said channel to bend a portion of said blank around said forming punch.

55 2. In a flange forming apparatus, a stationary die block having an opening formed therein, a roller mounted in said block at one side of said opening, said roller being rotatable about a fixed axis and being formed with an axially extending channel having side and bottom walls, a yieldingly-supported pad which is located in said opening and upon which a blank may be arranged, said pad having a lateral extension which 60 overlies the bottom wall of said channel and

which has an under side normally spaced from and normally nonparallel with respect to said bottom wall, and a forming punch which is movable to engage said blank and to force said pad with said blank into said opening, said extension being engageable with the bottom wall of said channel to rotate said roller and thereby cause the side wall of said channel to bend a portion of said blank around said forming punch.

3. In a flange forming apparatus, a die block having an opening formed therein, rollers mounted in said block at opposite sides of said opening, each of said rollers being formed with an axially extending channel having side and bottom walls, a yieldingly-supported pad which is located between said rollers and upon which a blank may be arranged, and a forming punch which is movable to engage said blank and to force said pad with said blank into said opening, said pad being engageable with the bottom walls of said channels to rotate said rollers in opposite directions and thereby cause the side walls of said channels to bend portions of said blank around said forming punch.

4. In a flange forming apparatus, a die block having an opening formed therein, rollers mounted in said block at opposite sides of said opening, each of said rollers being formed with an axially extending channel having side and bottom walls, a yieldingly-supported pad which is located between said rollers and upon which a blank may be arranged, said pad having a body portion and laterally extending flanges, the latter

overlying the bottom walls of said channels, and a forming punch which is movable to engage said blank and to force said pad with said blank into said opening, the flanges of said pad being engageable with the bottom walls of said channels to rotate said rollers in opposite directions and thereby cause the side walls of said channels to bend portions of said blank around said forming punch.

5. In a flange forming apparatus, a die block having an opening formed therein, rollers mounted in said block at opposite sides of said opening, each of said rollers being formed with an axially extending channel having side and bottom walls, a pad which is located between the side walls of the channels in said rollers and upon which a blank may be arranged, said pad having a body portion which extends below the bottom walls of said channels and laterally extending flanges which overlie said walls, means for normally holding said pad in a position in which the under sides of said flanges are spaced from and nonparallel with respect to said bottom walls, and a forming punch having receding side walls and which is movable to engage said blank and to force said pad with said blank into said opening, the under sides of the flanges of said pad being engageable with the bottom walls of said channels to rotate said rollers in opposite directions and thereby cause the side walls of said channels to bend portions of said blank around said forming punch.

KARL HERZOG.
